BOOKHOLDER

Elmer V. McCollum, Baltimore, Md.

Application July 28, 1952, Serial No. 301,221

5 Claims. (Cl. 45—80)

1

This invention relates generally to book holders and more particularly to an improved book holder of the body-supported type.

Book holders of this general type are known in the art and as a rule are characterized by a number of undesirable features. Among these are an excessive weight making the book holder tiresome to use, a lack of lateral or longitudinal stability with respect to the supporting body so as to require the use of the hands, a limited adjustability and a difficulty in making the available adjustments rendering the device unsuitable for enfeebled persons, a lack of flexibility of use so as to be single purpose devices, and an unnecessarily complicated structure rendering the book holder unnecessarily difficult and expensive to manufacture.

Accordingly, the chief object of the present invention is to provide an improved light weight book holder which will obviate the above mentioned undesirable features characterizing known structures.

Another important object of the present invention is to provide an improved book holder which may be supported on the thighs and braced against the trunk of the body so as to hold a book steady and at the proper level and angle for reading by any individual without requiring the use of the hands.

Another important object of the present invention is to provide a book holder of the type described which may be readily adjusted with a minimum of effort by aged or invalid persons as reading, etc., progresses.

A further important object is to provide a portable, lightweight book holder in which part or all of a set of adjusting means may be manipulated so as to vary the height, angular position or closeness to the body of the supported book in two or more ways.

A still further important object is to provide an improved body supported book holder which may be used while the person is sitting up or lying down, as a bed table, or which may be folded into a compact unit for storage purposes.

Other objects and advantages of the invention will become apparent during the course of the following description.

In the drawings I have shown one embodiment of the invention. In this showing:

Figure 1 is a side elevational view showing the book holder comprising the present invention in operative position;

Figure 2 is a front elevational view of the invention;

Figure 3 is a rear elevational view thereof; and

2

Figure 4 is a side elevational view of the book holder in collapsed or folded position for storage.

Referring to the drawings, numeral 10 designates the book holder as a whole which comprises essentially a base 12, a book support 14 and a connecting standard 16. The book holder is preferably formed of wood which is not cold to the touch and hence more desirable to the aged or invalids, although it may also be readily formed from metal or plastic materials.

The base 12 is of elongated rectangular shape and is provided with a pair of slots 18 between its central and end portions which extend from its front to its back edges. A second pair of somewhat shorter slots 20 are formed in the top surface of the base 12 also between its center and ends and these slots also extend longitudinally of the base and centrally of and open into the slots 18.

Each of the slots 18 receives the end of a flat, elongated and rectangular stabilizing arm 22 which is of only slightly less thickness than the slots so that the arms are snugly received therewithin. The ends of the arms 22 are provided with threaded apertures 24 for the reception of large wing bolts 26 which bear against the upper surface of the base 12 and project through the vertical slots 20. It will be readily apparent that the ends of the stabilizing arms 22 may be slid along the slots 18 as the wing bolts 26 are slid along the slots 20 and the arms as a whole may be pivoted about the wing bolts in varied angular positions, and clamped tightly in the desired position to the base 12.

The base 12 is provided at its midpoint with a transversely extending upstanding plate 28 having an elongated slot 30 formed therein and the base 29 of the plate 28 may be of greater width so as to form a support for the standard 16 when the book holder 10 is in the folded or storage position. (Figure 4.)

The standard 16 is formed as an H-shaped member and the ends of its upper and lower legs are respectively provided with aligned apertures one each of which is threaded. The lower legs 45 of the standard 16 are spaced apart a distance slightly greater than the thickness of the plate 28 to which they are pivotally and slidably connected by means of a large wing bolt 32 which passes through one of the unthreaded apertures, 50 the slot 30 and into the threaded aperture of the lower legs of the standard 16. Thus, the standard may be tightly clamped to the plate 28 after it has been adjusted to the correct position with respect thereto.

The book support 14 is provided on its rear or under surface with a depending plate 34 having

a slot 36 to and through which the upper legs of the standard 16 are pivotally and slidably connected by a large wing bolt 38 in the same manner as described in connection with the lower legs. The book support 14 comprises a flat plate which in normal usage is maintained in an inclined position as shown in Figure 1. The lower edge of the book support 14 is provided with a ledge 40 of suitable width as is conventional.

It will be noted that each of the wing bolts 26, 32 and 38 are of substantial size in order that they may be turned by the palm of the hand so as to be readily tightened or loosened by invalids having normally inadequate strength in their fingers. Although the wing bolts 32 and 38 are shown 15 positioned for use by right-handed persons, they may obviously be arranged on the left side for left-handed persons.

In use, the book holder 10 is placed transversely across the thighs of a person in sitting position with the wing bolts 26 loosened so that the arms 22 may be freely pivoted or slid in the slots 18. The outer ends of the arms are swung snugly against the hips or soft fleshy body portion where the hips should be to thus stabilize the base 12 and hold it and the book support 14 (when in adjusted position) completely steady for reading without requiring the use of the hands. The relative positions of the base 12, standard 16, and book support 14 are now adjusted until, as illustrated in Figure 1, the book B is supported in the optimum position for reading as to height, closeness to the eyes, and angle of the plate 14 with respect to the vertical.

It will be noted that in any adjusted position such as shown in Figure 1, the weight of the book B is supported on the base 12 and the stabilizing arms 22 and the weight is thus between its three point support and steadiness is assured. The book holder 10 is readily used as a table by changing the angle of the plate 14 and while lying in bed by adjusting the plate to proper position as in the sitting position.

An important feature of the invention resides in the combinations of adjustment made possible by the structure making its use and manipulation by invalids or enfeebled persons extremely easy and simple. For example, the angle of the book support on plate 14 may be readily varied by loosening the wing bolt 38 and pivoting the plate thereabout as desired. Or instead, the wing bolt 32 may be loosened and the plate and standard pivoted thereabout until the desired angular change is effected or pivoting about both wing bolts may be effected.

The height of the plate 14 may be varied by pivoting the standard 16 about the wing bolt 32 or sliding the wing bolt 38 in the slot 36 or both.

The distance of the book support 14 from the eyes of the user may be varied by sliding or pivoting the standard in either or both of the slots 30 and 36.

It will now be readily apparent that the book holder comprising the present invention relieves the user from the necessity of supporting the book with his hands while reading, enables the book to be held steady without motion due to the tremor of fatigued arm muscles, permits the book to be moved toward or away from the reader and angularly so as to maintain the page in proper reading position, and leaves the hands free for flattening or turning the page. The book holder is light in weight, strongly constructed, may be economically manufactured and when not in use, may be swung to a horizontal position to occupy but little space for storage or shipping purposes.

It is to be understood that the form of my invention herewith shown and described is to be taken as a preferred example of the same and that various changes in the shape, size and arrangement of parts may be resorted to without departure from the spirit of the invention or the scope of the subjoined claims.

I claim:

1. A book holder of the body supported type comprising an elongated base adapted to rest on and transversely of the thighs, a pair of arms adapted to rest on the thighs and projecting from opposite ends of said base to rigidly engage the hips and stabilize the holder against the weight of a book, a standard mounted on said base, and a book support mounted on said standard, said arms being slidably and pivotally connected with said base to accommodate for dimensional variations of the body and including means for maintaining an adjusted position.

2. A book holder as recited in claim 1 wherein said standard is slidably connected to said base.

3. A book holder as recited in claim 1 wherein said standard is pivotally and slidably connected to said base.

4. A book holder as recited in claim 1 wherein said standard is slidably connected to said base and said book support.

5. A book holder as recited in claim 1 wherein said standard is pivotally and slidably connected to said base and said book support.
